DESIGN FOR A PERFUME BOTTLE OR THE LIKE

Bertha H. Ogden, New York, N. Y., assignor to Babs Creations, Inc., New York, N. Y., a corporation of New York

Application February 14, 1940, Serial No. 90,245

Term of patent 3½ years

To all whom it may concern:

Be it known that I, Bertha H. Ogden, a citizen of the United States and a resident of the city of New York (Borough of Manhattan), county and State of New York, have invented a new, original, and ornamental Design for a Perfume Bottle or the like, of which the following is a specification, reference being had to the accompanying drawing, forming part thereof, in which—

Figure 1 is a front elevation of a perfume bottle showing my design;

Figure 2 is a rear elevation of the bottle; and Figure 3 is a top plan view of the bottle.

I claim:

The ornamental design for a perfume bottle or the like, substantially as shown.

BERTHA H. OGDEN.
